US0D1023743S

(12) **United States Design Patent** (10) **Patent No.:** **US D1,023,743 S**
(45) **Date of Patent:** **** Apr. 23, 2024**

(54) **PACKAGING**

(71) Applicant: **GUANGDONG YUEDONG
MECHANICAL INDUSTRY CO.,
LTD.**, Shantou (CN)

(72) Inventor: **Yueyun Li**, Shantou (CN)

(**) Term: **15 Years**

(21) Appl. No.: **29/842,452**

(22) Filed: **Jun. 14, 2022**

(51) LOC (14) Cl. **09-03**

(52) U.S. Cl.

USPC **D9/502**; D9/429

(58) **Field of Classification Search**

USPC D9/414, 415, 418, 420, 421, 422, 423, D9/424, 425, 428, 429, 430, 431, 432, D9/434, 455, 456, 457, 499, 500, 501, D9/502, 503, 504, 722, 737, 748, 655, D9/661, 707, 711, 713, 702; D7/387, D7/391, 392, 392.1, 396.1, 396.2, 396.3, D7/396.4, 397, 398, 401.1, 507, 509, 510, D7/511, 538, 900, 600, 601; D3/201, D3/202, 203.1, 203.2, 203.5, 203.8, 204, D3/205, 206, 207, 212, 276, 282; D28/91, 91.1; D34/1, 5, 6, 7, 8, 9, 10, D34/11; D19/113, 114, 135; D6/682.3, D6/682.4; D24/227

CLAIM

The ornamental design for a packaging, as shown and described.

DESCRIPTION

FIG. 1 is a front elevational view of a packaging showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof; and,

FIG. 8 is a second perspective view thereof.

1 Claim, 8 Drawing Sheets
